UNITED STATES PATENT OFFICE.

FRANK D. MERSEREAU, OF ORANGE, NEW JERSEY.

DESIGN FOR A CUSPIDOR.

SPECIFICATION forming part of Design No. 17,358, dated May 24, 1887.

Application filed October 5, 1886. Serial No. 215,413. Term of patent 7 years.

To all whom it may concern:

Be it known that I, FRANK D. MERSEREAU, of Orange, Essex county, New Jersey, have invented and produced a new and original 5 Design for a Cuspidor, of which the following is a specification.

The nature of my design is clearly shown in the accompanying drawings, in which—

Figure 1 is a rear view; and Fig. 2 is a trans- 10 verse section on the dotted line, Fig. 1.

The said design consists in a cuspidor having the conventionalized appearance of the well-known sunflower.

As seen in the accompanying figures, the 15 sides of the cuspidor are represented by a series of distinct petals, *a*, the central portion, *b*, be-

ing of irregular surface to increase the similitude of the design with that of a sunflower. An extension, *c*, is located at one side, in imitation of a stem.

20

I claim—

The design for a cuspidor, as herein shown and described, the same consisting of a conventionalized representation of a sunflower, composed of a central portion of irregular appearance, a surrounding portion in imitation of petals, and an extension representing a stem, as specified.

FRANK D. MERSEREAU.

In presence of—

WILLIAM V. H. HICKS,
A. SIDNEY DOANE.
